UNITED STATES PATENT OFFICE.

JULIUS C. UHLARIK, OF VALHALLA, NEW YORK, ASSIGNOR TO ROBINS CONVEYING BELT CO., A CORPORATION OF NEW JERSEY.

REVOLVING SHAKER SCREEN.

1,423,370.

Specification of Letters Patent. Patented July 18, 1922.

Application filed June 16, 1919, Serial No. 304,619. Renewed December 7, 1921. Serial No. 520,762.

To all whom it may concern:

Be it known that I, JULIUS C. UHLARIK, a citizen of Hungary, residing at Valhalla, in the county of Westchester and State of New York, have invented a new and useful Improvement in Revolving Shaker Screens, of which the following is a specification.

One object of my invention is to provide a screen for efficiently separating random sized particles of coke, coal, or other material into particles of uniform sizes by imparting to the screen and the material an improved vibratory motion having a considerable upward component to agitate and sift the smaller particles through the screen and to jar the larger particles off the screen.

Another object of my invention is to provide an oscillating screen frame carrying a screen plate having a complex cycle of motion in which half of each cycle imparts a centrifugal throw to the particles to agitate and prevent them from clogging the holes in the screen plate, and also to provide means for producing during each cycle a jar or shock. In the preferred construction, this result is attained by fastening the screen plate at each end only, leaving the central portion loose and thus free to flap up and down on the screen plate frame.

Another object of my invention is to effect such screening by an improved mechanism in which the oscillation of the screen frame and plate is counterbalanced and thus localized where it does useful work, saving unnecessary wear and tear on the machine and its foundations.

Another object of my invention is to actuate the screen plate by means of an improved mechanism having several parallel shafts provided with eccentrics driven in synchronism, to counterbalance the eccentric oscillatory motion of the screen plate and frame by weights positioned on the shafts diametrically opposite to the throws of the eccentrics, and to cause the screen plate to vibrate without shaking its frame to pieces.

Another object of my invention is to provide freedom of movement in the direction of the length of the screen for the bearings of the driven shaft, for adjustment of the chain connecting it to the driving shaft, and to prevent the wrecking of the machine in the event of the chain breaking and al-

lowing the eccentrics to get out of synchronism.

The screens heretofore in use are usually suspended by hangers disposed at a slight angle to the vertical and reciprocated more or less longitudinally and horizontally, which imparts analogous movement to the material. This motion permits the long and irregular shaped particles to hang in the holes of the screen plate, thus clogging the holes and reducing the capacity of the screen. To dislodge these particles all sorts of "knockers" have to be resorted to, and these particles have sometimes to be removed by an attendant provided with a sledge hammer. When the older types of screens are run at a high speed, the clogging can be reduced, but the life of the screen is then materially shortened.

In operation, the most conspicuous difference between my invention and the older types appears to be in the motion imparted to material on the screen. In the common types the material slides horizontally, the screen being set at an angle to the horizontal so that the sliding of the material takes place in a general downward direction. In my screen, however, the material is jarred on the loose central portion of the screen plate, agitated and thrown up at each cycle by centrifugal force and, due to the inclination of the screen, falls some distance ahead of its former location, the important factors governing the motions of this material being the speed of rotation of the eccentrics, their degree of throw and the inclination of the screen. It is interesting to note that the motion of my screen is in an orbit or endless path in which the jarring of the loose central portion of the screen plate causes higher frequency vibrations to occur; however the general motion is in a more or less circular orbit rather than reciprocating, and this feature facilitates counterbalancing.

In addition to the foregoing objects, others will appear from the detailed description and be pointed out in the claims.

Reference is made to the accompanying drawings forming a part of this specification and in which like characters indicate like parts throughout the several figures.

Fig. 1 is a plan view of my device, partly

broken away in order to show some of the lower parts in full lines.

Fig. 2 is a longitudinal sectional elevation taken on line 2-2 of Fig. 1 looking in the direction of the arrows.

Fig. 3 is a cross section taken on line 3-3 of Fig. 1.

Fig. 4 is a sectional view taken on line 4-4 of Fig. 3.

10 Fig. 5 is an enlarged sectional view taken on line 5-5 of Fig. 3.

Fig. 6 is a sectional view taken on the line 6-6 of Fig. 3.

15 Fig. 7 is a side elevation of one of the shafts.

Fig. 8 is an enlarged cross section taken on the line 8-8 of Fig. 7.

Fig. 9 is a curve plotted to show approximately the cycle of motion of my screen.

20 The numerals 10 and 11 indicate the side castings and the numerals 12 and 13 the end castings which collectively constitute the base of my revolving shaker screen. These castings are bolted together by bolts 14 and

25 15 as best shown in Fig. 2. The base carries pillow blocks 16, 17, 18 and 19, each of which may be adjusted to the right or left as shown in Figs. 1 and 2 by means of the adjustment bolts 20, which pass through

30 lugs 21 in the castings 10 and 11. The adjustment provided by these bolts has a double purpose, first to facilitate the alignment of the shafts 22 and 23 and second to facilitate the adjustment of the centers 35 around which the chain 24 travels.

The pillow blocks 16, 17, 18 and 19 are all similar, and each consists of a lower half 25 and a cap 26 as particularly shown in Fig. 6. The bolts 27 clamp the upper and 40 lower halves of each pillow block together and the bolts 28 clamp the lower halves 25 to the castings 10 and 11. These bolts 27 and 28 pass through longitudinal slots 29 in the castings 10 and 11 in order that the pillow blocks 16, 17, 18 and 19 may be adjusted longitudinally by the adjustment bolts 20. The pillow blocks 16, 17, 18 and 19 are severally provided with grease cups 30.

45 The driving shaft 22 is provided (at the left of Fig. 7) with a keyway 31, by which the sprocket 32 is fastened upon it; to the right of the keyway 31 a journal portion 33 is shown which is journaled in the pillow block 18. At the right of the journal portion a keyway 34 is provided to hold one of the split collars 35 from rotation; at the right of the keyway 34 a shoulder 36 and an eccentric 37 are provided; at the right the shaft 22 resumes its full diameter 38; at

55 the right of the full diameter portion an eccentric 39, a shoulder 40, a keyway 41 for another split collar 35, a journal portion 42, to be journaled in pillow block 16 and a keyway 43 to secure the main driving pulley 44 are shown.

The other shaft 23 is similar to shaft 22, excepting that it is not extended to contain a keyway corresponding to keyway 43 of shaft 22. Shaft 22 may be driven through the pulley 44 from any source of power. Shaft 22 carries at the keyway 31 the sprocket 32 surrounded by the chain 24 which connects it in driving relation to the driven sprocket 45 which is keyed on the driven shaft 23. When the sprockets 32 and 45 are of the same diameters as in the preferred construction, the shafts 22 and 23 rotate in synchronism.

The eccentrics 37 and 39 of the shaft 22 are contained in inverted pillow blocks 49 and 490, each of which consists of a lower half 50 and an upper half 51 as indicated in Fig. 2. These pillow blocks are provided with grease cups 52. They are bolted together with bolts 53 and to the side angle irons 56 of the screen plate frame by both bolts 53 and 54. The screen plate frame consists of the side angle irons 56 and end angle irons 57, which are braced by gusset plates 58 and riveted together by rivets 59 as shown particularly in Fig. 1.

The end angle irons 57 are provided with round washers or spacers 60 which support the perforated screen plate 61.

Flat head machine screws 62 pass through the plate 61, the washers 60 and the end angle irons 57 holding the plate 61 securely at each end. The side angle irons 56 are provided with spacers 63 which are riveted to them by counter sunk head rivets 64 as particularly shown in Fig. 1 and the spacers are beveled at their right hand ends in order to permit any particles which may collect on top of the side angle irons 56 to be jarred off toward the center of the screen plate 61.

It should be noted that the screen plate 61 merely rests upon the spacers 63 and so is free to jar upon them as will be more fully explained hereafter.

At the sides of the angle irons 56, strips 65 of bent sheet iron are attached in any suitable manner for the purpose of preventing the falling off, at the sides, of material passing down the incline of the screen.

At the upper or right hand end of the screen plate 61 according to Figs. 1 and 2, deflector angle irons 66 are secured by rivets 67 to the screen plate 61 as best shown in Fig. 1, to center the material flowing on to the screen at the upper or right hand end thereof.

Under the side angle irons 56 are mounted bearing guides 68, which are bolted to the angle irons 56 by bolts 69. Between these guides and the angle irons 56 are mounted bearings 70 and 71, for the eccentrics 47 and 48 of shaft 23. Each of these bearings consists of an upper half 700 and a lower half 701 which are bolted together with bolts 702.

These bearings 70 and 71 have freedom of movement in the direction of the length of the screen as best shown in Fig. 2, to provide for the increase or decrease of the distance between the centers of the shafts 22 and 23, which may be occasioned by the adjustment of the pillow blocks 16, 17, 18 and 19 or by any change in the distance between the eccentric centers, such for instance as either accidental breakage of the chain or intentional or accidental nonsynchronism of the eccentrics.

Through the bearing guides 68 slots 73 are provided for the stems 74 of the grease cups 75 of the bearings 70 and 71 which lubricate the eccentrics 47 and 48 of the shaft 23.

Shafts 22 and 23 are provided with split collars 35 as particularly shown in Fig. 5. These split collars each have an upper half 76 keyed to the shafts 22 and 23 by keys 77 and provided with set screws 770. Each split collar 35 also has a lower half 78, and the halves are clamped on to the shafts 22 and 23 by bolts 79 having nuts and lock nuts 80. These bolts extend and pass loosely through the counterweights 81 and are fastened in place by the nuts and lock nuts 82. The counterweights 81 can be adjusted to or from the centers of the shafts 22 and 23 by adjusting the nuts 82 and thus provide for proper counterbalancing of the screen frame and the members attached to it. The counterweights are substantially diametrically opposite to the throw of the eccentrics in order to relieve vibration from pillow blocks 16, 17, 18 and 19 and the members supporting them.

Referring to Fig. 9 in which a curve of the cycle of motion of the middle portion of the screen plate 61 and the screen frame is approximately plotted, the neutral position of each cycle is indicated by the horizontal line 83. The screen plate frame and the screen plate 61 rise together and the motion is indicated by the curve marked 84. The screen plate, owing to its inertia and to its being merely supported but not attached upon the spacers 63, lags at the upper part of the cycle and follows the dotted curve marked 85. The frame, being positively driven by the eccentrics, continues to follow the circular orbit of curve 84. At the point marked 87 a jar is produced by the spacers 63 coming in contact with and abruptly overcoming the inertia of the plate 61 and forcing it to again coincide in its motion with that of the plate frame. Beyond this point induced high frequency vibrations are probably developed in the plate 61 and are indicated by the dotted irregularities 88 of line 85.

This jar appears to be of material value in the operation of the screen.

Generally speaking, the action of my de-

vice may be summarized as follows: The material is introduced upon the screen plate at the right, according to Figs. 1 and 2, and travels toward the left, the fines dropping through the screen plate and the coarser particles falling off at the extreme left, according to the same figures. During its travel, each particle is thrown up by the centrifugal motion of the screen plate and toward the left, as particularly shown in Fig. 2, by the inclination of the screen. The jarring action between the particles and the screen plate causes the material to be periodically thrown out of contact with the plate and the agitation of the material thus facilitates its flow from right to left as well as the separation of the fines from the coarser particles.

At the right of Fig. 2 there is indicated by dot and dash lines 1000 the end of another screen similar to the one described, which may be operated in series to screen coarser sizes of material, but it is common practice to operate screens in tandem.

I do not limit myself to the exact construction shown, but variations may be made in accordance with progress in the art and the requirements of the particular materials to be screened, without departing from the spirit of the invention.

I claim:

1. A screen frame, means to move it in a circular orbit, consisting of parallel shafts provided with eccentrics, adjustable counterbalance means at the eccentrics, a bearing for one of the eccentrics having freedom of motion longitudinally of the frame, and a screen plate mounted loosely upon the frame to cause the plate, due to its inertia, to travel in an orbit of its own, alternately lagging behind the orbit of the frame and jarring upon it when the orbits again coincide.

2. A screen frame, means to move it in a circular orbit, consisting of parallel shafts provided with eccentrics, collars mechanically fastened at the eccentrics, adjustable counterbalance means attached to the collars, a bearing for one of the eccentrics having freedom of motion longitudinally of the frame, and a screen plate mounted loosely upon the frame to cause the plate, due to its inertia, to travel in an orbit of its own, alternately lagging behind the orbit of the frame and jarring upon it when the orbits again coincide.

3. In a self-contained rotary shaker screen, the combination of a base consisting of side members provided with bearings, end members connecting the side members, a screen frame, means to move it in a circular orbit, consisting of parallel shafts in the bearings and provided with eccentrics, collars mechanically fastened at the eccentrics, adjustable counterbalance means attached to the collars, a bearing for one of the eccentrics

1 having freedom of motion longitudinally of the frame, and a screen plate mounted loosely upon the frame to cause the plate, due to its inertia, to travel in an orbit of its own, 5 alternately lagging behind the orbit of the frame and jarring upon it when the orbits again coincide.

4. A screen frame, a screen plate attached to flex thereon, means to impart an orbital 10 oscillation to said frame in a plane normal to and longitudinal to said plate, and impact means on said frame for said plate.

5. A device of the character described comprising a screen frame, a screen plate of longitudinal form carried by said screen frame, 15 one portion of said screen plate being secured to said screen frame and another portion of said screen plate being loose relative to said screen frame so as to enable said 20 screen plate to flex relatively to said screen frame, means to impart an orbital oscillation to said frame, in a plane extending in the direction of the length of said plate, and impact means carried by said frame for receiving the impact of the loose portion of 25 said screen plate.

6. In a device of the character described the combination of a screen frame provided with a surface for receiving impact, a screen 30 plate carried by said screen frame and extending across said surface, said screen plate being made of such material as to render said screen plate capable of flexure, said screen plate having its end portions connected with said screen frame and having its intermediate portion free and so disposed as to engage said surface except when said screen plate is flexed, and mechanism connected with said screen frame for imparting 35 thereto an orbital oscillation in order to cause said intermediate portion of said screen plate to swing away from said surface and to swing back against the same.

7. In a shaker screen the combination of 45 a screen frame, means for imparting an orbital oscillation thereto, a screen plate connected with said screen frame and controllable by said orbital oscillation thereof for the purpose of causing said screen plate 50 to flex, and means for suddenly stopping the flexure of said screen plate.

8. In a shaker screen the combination of a screen frame, impact mechanism carried thereby, a screen plate having portions secured to said screen frame and having another portion disposed adjacent said impact mechanism, said screen plate having a longitudinal form and being flexible in the general direction of its length, said screen plate 55 being so disposed relatively to said screen frame that said portion of said screen plate located adjacent said impact mechanism can

have considerable movement of an oscillatory character relative to said impact mechanism owing to the flexure of said 65 screen plate, and means for imparting to said screen frame an orbital oscillation in a plane extending in the general direction of the length of said screen plate.

9. In a device of the character described, 70 the combination of a screen frame, a member mounted thereon and adapted to serve as a support, a flexible plate carried by said frame and extending across said member, said flexible plate being connected with 75 said screen frame upon opposite sides of said member, so that when said plate is flexed the proximate middle portion thereof is moved out of engagement with said member, and means for imparting to said 80 screen frame an orbital movement sufficiently violent to throw said proximate middle portion of the plate momentarily out of engagement with said member.

10. In a device of the character described, 85 the combination of a screen frame provided with impact mechanism, a flexible screen plate mounted upon said screen frame and provided with a portion loose relatively to said impact mechanism and normally tending to rest thereupon, the screen plate being provided with end portions secured to said screen frame in such manner as to enable said first mentioned portion of said screen frame to swing bodily away from said 95 impact mechanism whenever the screen plate is flexed, and means for imparting to the screen frame an orbital movement sufficiently violent to cause flexure of said screen plate.

11. In a device of the character described, 100 the combination of a screen frame, a flexible screen plate having some portions secured to said screen frame and having other portions free to swing away bodily from the general position of said screen frame to the 105 extent permitted by the flexure of the screen plate, means for imparting to the screen frame an orbital oscillatory movement sufficiently violent to cause the screen plate to flex, and stop mechanism for suddenly arresting the motion of the screen plate after 110 each flexure thereof.

12. A revolving shaker screen having a base supporting parallel shafts designed to be connected together and driven in synchronization by means of a chain, eccentrics on the shafts, a screen frame supported by a rigid bearing on one of the eccentrics and a free bearing designed to prevent wrecking of the machine in the event of breakage of the 115 chain, on the other eccentric, and a screen plate mounted upon the screen frame.
